(57) CLAIM

The ornamental design for a cap with a product having a stripe, as shown and described.

DESCRIPTION

FIG. 1 is a perspective view of a cap with a product having a stripe showing my new design;

FIG. 2 is a front view thereof;

FIG. 3 is a bottom plan view thereof;

FIG. 4 is a left side view thereof;

FIG. 5 is a back view thereof;

FIG. 6 is a right side view thereof;

FIG. 7 is a top plan view thereof;

FIG. 8 is a perspective view of a second embodiment of a cap with a product having a stripe;

FIG. 9 is a front view thereof;

FIG. 10 is a bottom plan view thereof;

FIG. 11 is a left side view thereof;

FIG. 12 is a back view thereof;

FIG. 13 is a right side view thereof; and,

FIG. 14 is a top plan view thereof.

In all views, the stippling indicates color, but not a particular color.

The broken lines in the drawings are for illustrative purposes only and form no part of the claimed design.
